(57) **CLAIM**

The ornamental design for a geodetic apparatus, as shown and described.

DESCRIPTION

FIG. 1 is a front, right side perspective view of a geodetic apparatus showing our new design;
FIG. 2 is a front, left side perspective view thereof;
FIG. 3 is a rear, left side perspective view thereof;
FIG. 4 is a rear, right side perspective view thereof;
FIG. 5 is a front elevation view thereof;
FIG. 6 is a rear elevation view thereof;
FIG. 7 is a top plan view thereof;
FIG. 8 is a bottom plan view thereof;
FIG. 9 is a left side elevation view thereof; and,
FIG. 10 is a right side elevation view thereof.
The broken lines depict portions of the geodetic apparatus that form no part of the claimed design.
